UNITED STATES PATENT OFFICE.

GEORGE NEWTON FRAZER, OF EUGENE, OREGON.

TAKE-DOWN COOK-RANGE.

1,097,417.

Specification of Letters Patent.

Patented May 19, 1914.

Application filed August 5, 1913. Serial No. 783,082.

To all whom it may concern:

Be it known that I, GEORGE N. FRAZER, a citizen of the United States, and a resident of Eugene, in the county of Lane and State 5 of Oregon, have made certain new and useful Improvements in Take-Down Cook-Ranges, of which the following is a specification.

My present invention relates to a cook 10 range, and my object is to provide a cook range which may be separated into parts adapting it to be made into a compact form for more convenient transportation, and a further object of my invention is to provide 15 an improvement upon a similar type of cook range described and claimed in my Patent Number 1,062,450, granted May 20, 1913.

In the accompanying drawings which illustrate my present improvements, Figure 1 20 is a perspective view of the stove erected in operative position, with the oven and stove doors and the top plate removed. Fig. 2 is a similar view of the range top removed, Fig. 3 is a similar view of the oven bottom 25 removed, Fig. 4 is a similar view of the fire box end of the range removed, Fig. 5 is another similar view of the flue end of the range removed, and Fig. 6 is a central longitudinal section through the assembled 30 parts shown in Fig. 1.

Referring now to these figures, the two end sections, one being the fire box section A, and the other the flue section B shown in Figs. 4 and 5 respectively, are adapted to be 35 connected by upper and lower sections C and D respectively, shown in Figs. 2 and 3, so as to form a complete range structure with the exception of a back plate, top plate and the oven, and stove doors which have 40 been omitted in order that the range structure may more clearly appear.

The fire box section A is of substantially increased width with respect to the flue section B and is provided in its front wall with 45 openings a and a' respectively, communicating with the fire pot and the ash pit, its outer side being entirely closed by a wall a², and its inner side being provided with a plate a³, the upper and lower edges of which are 50 terminated some distance from the upper and lower edges of the section in a manner substantially similar to the inner plate b of the flue section B, most clearly shown in Fig. 5, the outer side of this flue section being 55 closed by an outer wall b'. The fire box and flue sections A and B are respectively

provided with legs a⁴ and b², and the flue section B is further provided with a vertical flue b³, the lower end of which opens inwardly below the lower edge of its inner 60 plate b and at the upper end of which is arranged a damper b⁴.

The upper range section C as particularly shown in Fig. 2, consists of a base c and front and rear walls c' and c² respectively, 65 the base c being provided with depending end lips c³ which are adapted for engagement over the upper edges of the inner walls a³ and b of the fire box and flue sections, so as to interlock the upper range section C 70 between the upper portions of the fire box and flue sections A and B, as shown in Fig. 1, the ends of the front and rear walls c' and c² of the upper range section C which project beyond the lips c³ of its base extending against the inner surfaces of the front and rear walls of the fire box and flue sections, as will be seen. The lower section or oven base D is adapted to connect the lower portions of the fire box and flue sections 80 A and B and to form the base of the oven, of which the inner plates a³ and b form the side walls and the base c of the upper section C forms the top. To this end section D consists of top and bottom walls d, front 85 and rear walls d' and end walls d² and d³ of which the later end d³ is provided with openings upon opposite sides of intermediate vertical walls d⁴, so as to establish communication between the interior of the 90 lower range section D and the spaces within the flue section B upon opposite sides of its flue b³. The end wall d³ is also provided with an opening communicating between the said intermediate vertical walls d⁴ so as to 95 establish communication with the flue b³, it being seen that these vertical walls d⁴ thus form a continuation of the flue and extend for only a portion of the length of the section D. The end walls d² and d³ are extended above the top wall d of the section in order to provide lips d⁵ which extend upwardly beneath the lower edges of the inner plates a³ and b, the front and rear walls d' being extended beyond the end walls in 100 order to project within sections A and B and the parts in engaged position. Thus with the sections assembled, as shown in Fig. 1, and damper d⁴ in the position shown in Figs. 1 and 5, the products of combustion 110 from the fire pot of section A will pass across the upper range section C and down-

wardly through the flue section B upon opposite sides of the flue b^3 , and it will be necessary for these gases to pass into and partly through the lower range section D before they find their way into the extension of flue b^3 in order to subsequently pass upward through the same. With the damper b^4 turned to horizontal position, the lower portion of the flue will be closed and the draft thus directed out through the upper portion thereof.

The basis of the fire box and flue sections A and B are provided with cleats a^6 and b^5 respectively, these cleats being adapted to be extended beneath the lower range section D when the several sections are assembled in order to coöperate with the upper and lower range sections effectively and rigidly lock the range parts or sections in operative position. Thus, it will be seen that I provide a range in four sections, which may be readily and quickly assembled and taken apart, and, when free from one another, may be conveniently stored in a minimum space, or packed together or separately, as desired.

I claim:

1. A take down range comprising a fire box section having an outer closed wall and an inner plate, the upper and lower edges of which terminate respectively below and above the upper and lower ends of the section, a flue section opposite to and facing the fire box section, having an outer closed wall and a central vertical flue and pro-

vided with an inner wall, the upper and lower edges of which terminate respectively below and above the upper and lower ends of the section, and intermediate upper and lower sections having end lips for engagement with the respective edges of the inner plates of the fire box and flue sections, and having extended front and rear walls projecting into the fire box and flue sections, said upper intermediate section being open at its top and the lower intermediate section having a top plate and being open at one end into the flue section and provided with inner vertical walls extending for a portion of its length and forming a continuation of the central flue of the flue section, all for the purpose described.

2. A take down cook range comprising a fire box section and a flue section forming opposite ends of the range, and upper and lower intermediate sections for spacing and connecting said fire box and flue sections whereby to form the oven, the said fire box and flue sections being provided with inner plates forming the side walls of the oven and the intermediate sections having lips whereby to lockingly engage the upper and lower edges of the said inner plates and support the several sections in assembled position.

GEORGE NEWTON FRAZER.
